UNITED STATES PATENT OFFICE.

WILLIAM E. NEWNAM, OF COLLINSVILLE, ILLINOIS, ASSIGNOR, BY MESNE ASSIGNMENTS, TO NATIONAL LEAD COMPANY, OF NEW YORK, N. Y., A CORPORATION OF NEW JERSEY.

MECHANICALLY-OPERATED SCOTCH HEARTH.

1,388,144.

Specification of Letters Patent. Patented Aug. 16, 1921.

Application filed April 3, 1916, Serial No. 88,673. Renewed November 4, 1918. Serial No. 261,144.

To all whom it may concern:

Be it known that I, WILLIAM E. NEWNAM, a citizen of the United States, and residing at Collinsville, in the county of Madison and State of Illinois, have invented a certain new and useful Improvement in Mechanically-Operated Scotch Hearths, of which the following is a specification.

This invention relates to smelting furnaces, and more particularly to smelting furnaces of the Scotch or ore hearth type, which are used for smelting lead.

A Scotch or ore hearth, especially as used in America, comprises a comparatively deep basin of cast iron, a water back having twyers at the lower end thereof positioned just above the basin, an apron which extends forwardly from the basin, and a hood which extends over the hearth. In the operation of such a furnace the basin is filled nearly full of lead, which is then melted by building a fire on the hearth. The ore and fuel are then placed so as to float on top of this bed or bath of molten lead in the basin and banked up against the water back. If a blast is now applied to the twyers, a part of the ore is reduced to molten lead, which settles in the basin, the unmelted clinker being used as a blast furnace product. In the operation of the hearth, the workman rabbles or works up the ore and fuel, (which is usually coke) banked against the water-back, this rabbelling being accomplished by inserting the rabbelling device, which is in the form of a bar, into the basin, and, using the front edge of the basin as a fulcrum, bearing down on the end of the rabbble so as to turn over and work up the material on the hearth and bring the gray clinker to the surface. This rabbelling proceeds from one end to the other of the hearth, and is succeeded by a leveling operation. In this leveling operation the workman will use a shovel and push back or level the material against the water back, the clinker being picked out and removed from the hearth for subsequent use in the blast furnace. The workman will then add small quantities of ore and fuel in ground condition. During the rabbelling operation the molten lead will overflow and discharge into molds to form pig lead. The fumes given off during the smelting operation pass upwardly and are caught by the hood, from

whence they pass to the bag house, where they are collected. Now the operation of such a hearth not only requires a considerable amount of manual labor, but, in view of the presence and escape of poisonous lead fumes, it is difficult to obtain and retain workmen.

In the operation of the usual hand rabbled ore hearth, the fume losses are not only great, but the recovery of metal is relatively small. This is due to the fact that the rabbelling is not only irregular, but the rabbled charge is exposed for considerable periods of time, thereby causing the oxidation of a considerable amount of lead which passes into the flue as fume.

Some of the objects of this invention, therefore, are to provide an improved furnace of the above type in which the rabbelling operation will be performed mechanically, so as to reduce the manual labor and increase the output of a furnace, and to provide means whereby the fumes are carried off so as not to escape in the vicinity of the workmen.

Another object is to provide a mechanically operated rabbelling device for a furnace of the above type which is simple in construction, effective in its operation, and reliable.

Further objects will appear from the detail description taken in connection with the accompanying drawings, in which:

Figure 1 is a front elevation of a furnace embodying this invention;

Fig. 2 is a section on the line 2—2, Fig. 1, showing the carriage and furnace in side elevation;

Fig. 3 is a detail plan view of the carriage;

Fig. 4 is a detail side elevation of Fig. 3, showing the clutch operating mechanism;

Fig. 5 is a detail section on the line 5—5, Fig. 1, showing the carriage feeding mechanism;

Fig. 6 is a side view of Fig. 5;

Fig. 7 is a section on the line 7—7, Fig. 2, showing the automatic stopping mechanism for the feeding mechanism;

Fig. 8 is a detail showing the clutch controlling mechanism for the feeding mechanism;

Fig. 9 is a section through the furnace,

and a side elevation of the rabbling device; the eccentric connections to the pawl and ratchet, move the carriage step by step from left to right, Fig. 1, along the hearth.

Fig. 10 is a detail section on the line 10—10, Fig. 9.

Referring to the accompanying drawings, 5 and more particularly, to Figs. 1, 2 and 9, 1 designates the furnace base, which is provided with a cast iron basin 2, an apron 3, and a water back 4 having twyters 5. The 10 water back extends along the back and sides of the hearth, and is cast hollow, as usual in Scotch hearth constructions, the water connection being shown at 6, while the blast pipe connection is shown at 7. A hood 8, of 15 usual construction, extends over the hearth and discharges into pipes 9, these pipes in turn discharging into a flue common to a number of furnaces and leading to the bag house. The hearth so far described may be 20 of usual construction, although it is for practical purposes, made longer than the usual Scotch or ore hearth.

Spaced from the main hood 8 is an exhaust hood 10 discharging into pipes 11 also 25 spaced from the pipes 9, and leading to a common flue which discharges into a stack. The space between the hoods will, therefore, be heated, and this heat will cause an induced draft between the hoods, which will 30 carry off any gases which may not be caught by the main hood. A spout 12 is formed on one end of the basin, and is connected by a duct 13 extending to the bottom of the basin, so that the overflow can discharge from the 35 spout into molds 14 carried by a carrier or carriage 15 movable on a track 16 across the end of the furnace.

Mounted in front of the furnace are pairs of braced standards 20, which carry rails 21. 40 A carriage 22, preferably of structural material, has wheels 23 and 24 running on the rails whereby the carriage is suspended for movement along the hearth. The wheels 23 are fixed to a shaft 25 on the carriage, and 45 to this shaft is fixed a ratchet 26, engaged by a pawl 27 on a pawl carrier 28, loosely mounted on the shaft and connected by a link 29 with an arm 30 pivoted on a bracket 31 fixed to a cross beam 32 of the carriage. 50 The arm 30 is provided with a series of apertures 33, any one of which is adapted to receive the cross pin 34 on the upper end of an eccentric rod 35, which carries at its lower end a strap 36 engaging an eccentric 55 37 on a shaft 38 mounted in bearings on the carriage 22. This shaft has loosely mounted thereon, but adapted to be clutched thereto, a gear 39 meshing with a pinion 40 on a shaft 41 also mounted in bearings on the 60 carriage, and having fixed thereto a fly wheel 42 and a gear 43 meshing with a pinion 44 on the shaft of an electric motor 45 mounted on the carriage. With this construction, the motor 45 will rotate the shaft 65 38 at reduced speed, and this will, through

Fixed to the shaft 38 at its left hand end 70 is a crank disk 50, the crank pin 51 of which is swiveled therein and terminates in a yoke 52 and a strap 53 pivoted at 54 on the yoke, and having a slot 55 therein adapted to align with a corresponding slot in the strap, so that when the two come in alignment a pin 560 can be inserted to connect the same. The strap is adapted to receive the end of a rabbling device 56 in the form of a bar, this rabbling device being retained by collars 57 and 58, a spring 59 being interposed 80 between the collar 58 and the yoke 52 so as to yieldingly connect the rabbling device with the crank pin. The free end of the rabbling device is supported by a fork 60 carried by a bracket 61 on the carriage 22. Rotation of the shaft 38 will thus cause the point of the rabbling device to perform a rabbling movement, corresponding closely to the movement given by the workman, in the elliptical path as shown in Fig. 9. On account of the yielding connection between the rabbling device and its operating mechanism, the accidental engagement of the point of the rabbling device with the basin or water back, or with a hard substance therebetween, will avoid breakage. Furthermore, the connection permits ready detachment of the rabbling device from its crank, so as to permit replacement.

The hub of the gear 39 has fixed thereto 100 a sprocket 65 connected by a chain 66 with a sprocket 67 loosely mounted on a counter-shaft 68, but provided with a jaw clutch 69 adapted to engage a clutch sleeve 70 splined on the shaft 68. The shaft 68 has fixed thereto a bevel gear 71 meshing with a co-operating bevel gear 72 fixed to a shaft 73 on the carriage 22, to which shaft are also fixed the wheels 24. The clutch sleeve 70 is normally out of engagement with the co-operating clutch 69, but is carried by an arm 74 pivoted at 75 on a cross beam 76 on the carriage 22, and connected by a link 760 with an arm 77 on a rock shaft 78 mounted in bearings on the carriage, and having an arm 79 to which is attached a link 80 provided with a handle, as shown in Fig. 1. When the link 80 is drawn down, the clutch sleeve 70 is thrown into engagement with the clutch 69 carried by the sprocket 67, so 110 that, if the pawl 27 is inactive, as herein-after described, the carriage will be moved by continuous movement from right to left, Fig. 1. Located in the path of the arm 74, and preferably fixed to one of the rails 21, 115 is a lug or projection 81, so that, when the carriage reaches a position where the rabble approaches the left end water back wall, the arm 74 will be engaged by the lug to disengage the clutch 70—69, and stop the carriage. 120

A shield 82 on a carrier 83 loosely mounted on the shaft 25 extends over the ratchet 26. This shield carrier is connected by a link 84 with an arm 85 on a rock shaft 86 mounted 5 in bearings between the rails 21. This rock shaft has an arm 87 connected with the upper end of a link 88, the lower end of which is connected to an arm 89 pivoted at 90 on the carriage. A spring 91 on the link bears, 10 at one end, against a collar 92 on the link, and, at the other end, against a bracket 93 on one of the rails 21. The gear 39 has a clutch jaw 920 coöperating with a clutch sleeve 930 splined to the shaft and normally 15 moved toward the clutch jaw 920 by a spring 94, one end of which bears against the clutch sleeve 930, and the other end of which bears against a collar 95 on the shaft. The collar 95 has a flange 96 provided with a cam 20 97 adapted to be engaged by a cam roll 98 on the arm 89. The free end of the arm 89 is guided by a post 980 on the cross beam 99 of the carriage, and is adapted to coöperate with a latch 100 pivoted at its lower end, 25 provided with a bevel tooth 101, and having a spring 102 which normally tends to move the latch to the left, Fig. 1, and to the right, Fig. 7. The rock shaft 86 has an arm 103 provided with a cam roll 104 adapted to 30 ride on a stationary cam 105 fixed to the right end, Fig. 1, of one of the rails 21.

Assuming the carriage to be at the left end of the hearth, but with the parts of the carriage in the position shown in Fig. 1, 35 that is, with the arm 89 down so that the clutch jaws 920 and 930 will be in engagement to clutch the gear 39 to the arm 89, with the clutch jaws 69 and 70 out of engagement, and with the shield 82 in a position 40 so that it will not be engaged by the pawl during its reciprocations, the operation will then be as follows: Rotation of the shaft will cause the rabbling device to move into and out of the material on the hearth, 45 in the path shown in Fig. 9, and this movement of the shaft 38 will, furthermore, cause the pawl to reciprocate and feed the carriage step by step. The crank connected with the rabbling device, and the eccentric 50 connected with the pawl are so relatively positioned that the pawl will move back over the ratchet, while the rabbling device moves from the position *a* to the position *b*, Fig. 9, in the direction of the arrow, and will 55 positively move the ratchet while the rabbling device moves from the point *b* to the point *a* in the direction of the arrow. The carriage is thus stationary while the rabbling device is moving into the material, and is fed 60 while the rabbling device moves out of the material on the hearth. The carriage will thus be fed step by step from the left to right, Fig. 1, and for each step the rabbling device 65 will execute one complete movement. By a proper proportioning of the feed, which can

be accomplished by adjustment of the pin 34 along the arm 30, a proper rabbling of the material on the hearth may be obtained.

As the carriage comes to the position shown in Fig. 1, that is, as the rabbling device approaches the right end wall of the water back, the cam roll 104 will ride on the cam 105, thereby oscillating the rock shaft 86 in the direction of the arrow, Figs. 1 and 7. This will throw the pawl shield 82 over the ratchet in the direction of the arrow, Fig. 7, to the position shown in that figure, so that the pawl 27 will be thrown out of engagement with the ratchet 26, whereby further oscillation of the pawl will be an idle movement, and the carriage will, therefore, come to rest. This movement of the rock shaft 86 will, furthermore, raise the link 88 and carry with it the arm 89, so as to throw the cam roll 98 in the path of the cam 97, whereby, upon rotation of the sleeve 930, the latter will be moved to the left, Fig. 8, and positively withdraw the clutch sleeve 930 out of engagement with the jaw 920, and thus disconnect the shaft 38 from the gear 39. The result is, therefore, that the shaft 38 will come to rest. The spring 94 is made strong enough so that the frictional engagement of the cam 97 with the roll 98 will act as a brake and stop the shaft in the position shown in Fig. 8. Furthermore, the cam 97 is so positioned on the shaft 38, and with respect to the crank 50, that the shaft will be stopped with the rabbling device in retracted position, and with the point thereof at the extreme retracted position *a*, Fig. 9. The upward movement of the arm 89, Figs. 1 and 7, will cause the free end thereof to snap past the tooth 101 on the latch 100, which will now take under the arm and lock it in raised position. It will, therefore, be seen that the carriage and the rabbling device will, at the end of the feeding movement of the carriage, be held in position with the operating mechanisms 100 therefor rendered inoperative.

To return the carriage, the workman will pull down on the link 80, thereby connecting the clutch jaws 69 and 70 and causing the carriage to move from right to left, Fig. 1, 115 to starting position, the step by step feeding mechanism, as well as the rabbling operating mechanism, remaining inoperative during this movement. At the end of the return movement, the clutch jaws 69-70 will be 120 automatically disconnected, as heretofore described. To again throw the step by step feeding mechanism and the rabbling operating mechanism into action, the workman will simply move the latch 100 to the right, 125 Fig. 1, which will drop the arm 89, thereby permitting the spring 94 to move the clutch jaw 930 into engagement with the clutch jaw 920, and throwing back the pawl shield 82. The step by step feeding mechanism will 130

then again be thrown into operation to feed the carriage along the hearth, and the rabbling operating mechanism will be thrown into operation to rabble the material on the 5 hearth. It will thus be noted that the carriage is fed, during the rabbling operation, with a slow step by step movement, and is returned by a continuous movement, the gearing being such as to give a slow feeding 10 movement and a quick return movement.

In the operation of this ore hearth, two men, a charger and a helper operate the furnace. A thin layer of concentrates having been spread over the charge on the 15 hearth, as soon as the ore is partially smelted, it becomes necessary to rabble; then the rabbling mechanism is set into action, the rabbler being moved step by step along the hearth, and as it moves along, it breaks 20 up the charge and draws a portion of it out on the apron. The impurities in the ore have a tendency to collect in lumps to form the gray slag, as the charge is broken up by the rabbler and drawn out, this gray slag 25 must be picked out and thrown to one side and the charge free from the slag must be pushed back onto the hearth. The helper, therefore, follows closely behind the rabbler, and with a long handled shovel pushes back 30 the loose charge, picking out the gray slag as he goes along and throwing this slag into a car for subsequent smelting.

When this is done, a new charge of fresh ore must be immediately spread over the 35 surface; consequently, closely behind the helper comes the charger, who spreads a thin layer of ore on the charge as fast as it is shoveled back by the helper, adding coke breeze as needed. At the end of the 40 rabbling operation, the carriage will come to rest and will then be returned to its starting point with the rabbler withdrawn and out of action. By the time that the carriage has returned, the portion of the charge on 45 the left of the furnace will have been smelted and is again ready to be rabbled, the operation again being performed as heretofore described. Periodically, the bar will be inserted into the passage 13 and the molten 50 lead will flow freely into the molds 14, which are then wheeled away.

In an ore hearth, it is not sufficient to merely rake the material, but it must be rabbled in a certain way. The prime purpose of the rabbler is, of course, to bring the gray slag to the top so that it can be 55 picked off by the helper. Moreover, the charge must not be exposed too much, for if this is done, the hot ore will oxidize and 60 pass into the flue as fume, thereby reducing the amount of metal which is extracted. It is, therefore, necessary in practical operation that a step by step movement be imparted to the carriage, so that the rabbler 65 is stationary in a direction along the hearth

while it is buried in the bed, and is moved while out of the bed. If this rabbler were fed along the hearth while in the bed, then it would drag the slag along the bed of ore and fuel, so that the slag would not be 70 moved to the top and onto the surface as is necessary in successful ore hearth operations. For practical and successful operations the rabbler must, therefore, be given a simple movement from the bottom to the 75 top of the bed on the hearth so as to work up the bed. Accordingly, a step by step movement is necessary and accordingly the carriage must be moved while the rabbler is withdrawn.

In the smelting of lead on an ore hearth, the smelting must be proceeded with for a certain length of time after rabbling and before again rabbling. If, of course, the rabbler would operate on the bed while it 80 is moving back as well as forth, then it would start to rabble a portion which has just been rabbled, and on which a fresh charge of ore had just been placed, before this portion had been smelted. In accordance with this invention the charge is rabbed in one direction while the return movement of the carriage is an idle one. Accordingly, each portion of the charge is given a certain amount of time for smelting before 85 it is again rabbled, and the smelting and rabbling, therefore, is uniform as to time and space. By rabbling the bed in one direction only and by constructing the mechanism so that the helper and charger can 90 follow right up behind the rabbler, each rabbled portion is exposed for a short period only, and is immediately covered as each portion is rabbled, and as each portion is rabbled, the slag is picked out of the same.

In view of the fact that the smelting of a charge requires in practice only about two minutes, and that any excess is not only a waste of fuel, but also of metal passing off as fume, it will be appreciated that any 100 mechanism or manipulation which closely regulates the timing of the rabbling and smelting operations, will secure the best results. In an ore hearth, the blast should be kept as low as possible consistent with 105 proper operation, because a high blast has a tendency to increase the temperature, causing volatilization of the metal. Moreover, the exhaust of the gases through the hood should not be any more than necessary to 110 keep the working atmosphere free from fume and dust; if the suction is excessive, part of the metal and ore is carried into the flue thereby reducing the extraction.

It will, therefore, be seen that there are a 115 number of factors entering into the successful operation of an ore hearth which determine the extraction. Accordingly, the length of a hearth, especially when mechanically rabbled is limited. A long continuous struc- 120

ture is impracticable because it is not elastic, since the temperature, exhaust, the rabbling and the addition of the ore and fuel, together with the metallurgical conditions generally, cannot be closely enough controlled

5 to secure the most efficient operation. Moreover, in a multiple structure, the operation of one part is dependent on the other, so that if one part operates improperly or freezes 10 up, the whole structure must be shut down.

A unitary hearth of a length sufficient to permit its attendance by a helper and a charger will secure the best results. Accordingly, the length of the hearth is pro-

15 portioned to correspond to the movement of the rabbler and to the period of smelting of the ore added to the hearth by operatives. In this way, where a smelting plant utilizes a number of such hearths, one hearth is inde- 20 pendent of all of the other hearths. As a practical proposition, therefore, a hearth eight feet in length attended by a helper and a charger, and in which the rabbler makes from thirty-five to forty round trips

25 per hour, secures the best results. Such a hearth can be operated by two operatives without interference, will secure the proper metallurgical conditions so as to utilize a minimum of fuel, and will enable the charge 30 to be kept covered as it is being rabbed, thereby reducing the fuel to a minimum and giving a maximum extraction. The regularity of the rabbling together with the regularity in covering the charge will not 35 only secure a regularity of the separation of the gray slag and regularity of the smelting, but will also reduce the fuel required, in that it enables the sulfur content of the ore to be better utilized for heating the charge.

40 It will thus be seen that the hearth is mechanically operated in so far as the operations can be performed mechanically. The most difficult and laborious operation,

45 namely, the rabbling operation, is performed mechanically, so that, with a given operating force, the output of a furnace will be very much increased. Moreover, it is not necessary for the workman to come so close

50 to the furnace, as the leveling can be performed with long handled shovels, and the danger of poisoning to the workman is, therefore, avoided. This poisoning is fur-

55 thermore practically completely obviated by the employment of the exhausting hood, which carries off any fumes which may not be caught by the main hood. The provision

60 of the auxiliary hood, spaced from the main hood and provided with an air space between the main hood and the carriage, will

65 not only facilitate the exhaust of the fumes from the hearth, but will also shield the carriage and the mechanism thereon against the radiated heat, so as to permit and facilitate lubrication and operation. By suspend-

spaced from the base or floor-line, the front of the furnace is left entirely clear for the workmen.

It is obvious that various changes may be made in the details of construction and manipulation without departing from the spirit of this invention, and it is, therefore, to be understood that this invention is not to be limited to the specific details shown and described.

Having thus described the invention, what is claimed is:

1. A smelting furnace, comprising, a Scotch hearth adapted to receive molten metal upon which floats the material to be smelted, a carriage mounted for movement along said hearth, a rabbling device mounted on said carriage and adapted to engage the material on said hearth, operating means for imparting a step by step movement to said carriage, and means for operating said rabbling device in co-operative relation with respect to said operating means, adapted to work up the material on said hearth.

2. A smelting furnace, comprising, a Scotch hearth adapted to receive molten metal upon which floats the material to be smelted, a carriage mounted for movement along said hearth, a rabbling device mounted on said carriage, means for moving said rabbling device into and out of the material on said hearth, and means for moving said carriage while said rabbling device is withdrawn, adapted to work up the material on said hearth.

3. A smelting furnace, comprising, a Scotch hearth adapted to receive molten metal upon which floats the material to be smelted, a carriage mounted for movement along said hearth, a rabbling device mounted on said carriage, means for moving said rabbling device into and out of the material on the hearth, and means imparting a step by step movement to said carriage, adapted to move said carriage while said rabbling device is withdrawn, and adapted to work up the material on said hearth.

4. A smelting furnace, comprising, a Scotch hearth adapted to receive molten metal upon which floats the material to be smelted, a carriage mounted for movement along said hearth, a rabbling device mounted on said carriage and adapted to engage the material on said hearth, operating means for moving said carriage along said hearth, adapted to work up the material on said hearth, means for returning said carriage, and means for operating said rabbling device constructed to cause said rabbling device to remain inoperative during the return of said carriage.

5. A smelting furnace, comprising, a Scotch hearth adapted to receive molten metal upon which floats the material to be smelted, a carriage mounted for movement

1. along said hearth, a rabbling device mounted on said carriage and adapted to engage the material on said hearth, operating means for imparting a step by step movement to said carriage, means for operating said rabbling device in coöperative relation with respect to said operating means, adapted to work up the material on said hearth, and means for returning said carriage.
10. 6. A smelting furnace, comprising, a Scotch hearth adapted to receive molten metal upon which floats the material to be smelted, a carriage mounted for movement along said hearth, a rabbling device mounted on said carriage, means for feeding said carriage along said hearth, means for operating said rabbling device in coöperative relation with respect to said feeding means, adapted to work up the material on said hearth, and means for returning said carriage while said rabbling device remains inoperative.
15. 7. A smelting furnace, comprising, a Scotch hearth adapted to receive molten metal upon which floats the material to be smelted, a carriage mounted for movement along said hearth, a rabbling device mounted on said carriage, means for feeding said carriage along said hearth, means for operating said rabbling device in coöperative relation with respect to said feeding means adapted to work up the material on said hearth, and means for imparting a quick return movement to said carriage.
20. 8. A smelting furnace, comprising, a Scotch hearth adapted to receive molten metal upon which floats the material to be smelted, a carriage mounted for movement along said hearth, a rabbling device mounted on said carriage, means for feeding said carriage along said hearth, means for operating said rabbling device in coöperative relation with respect to said feeding means adapted to work up the material on said hearth, and means for automatically stopping said carriage at the end of its feeding movement, and manually controlled means for starting said carriage.
25. 9. A smelting furnace, comprising, a Scotch hearth adapted to receive molten metal upon which floats the material to be smelted, a carriage mounted for movement along said hearth, a rabbling device mounted on said carriage, means for feeding said carriage along said hearth, means for operating said rabbling device in coöperative relation with respect to said feeding means adapted to work up the material on said hearth, and means for rendering said feeding and operating means inoperative.
30. 10. A smelting furnace, comprising, a Scotch hearth adapted to receive molten metal upon which floats the material to be smelted, a carriage mounted for movement along said hearth, a rabbling device mounted on said carriage, means for feeding said carriage along said hearth, means for operating said rabbling device in coöperative relation with respect to said feeding means adapted to work up the material on said hearth, and means for varying the feed.
35. 11. A smelting furnace, comprising, a Scotch hearth adapted to receive molten metal upon which floats the material to be smelted, a carriage mounted for movement along said hearth, a rabbling device mounted on said carriage, means for feeding said carriage along said hearth, means for operating said rabbling device in coöperative relation with respect to said feeding means, and means for stopping said carriage with said rabbling device in withdrawn position.
40. 12. A smelting furnace, comprising, a Scotch hearth adapted to receive molten metal upon which floats the material to be smelted, a carriage mounted for movement along said hearth, a rabbling device mounted on said carriage, means for feeding said carriage along said hearth, means for operating said rabbling device in coöperative relation with respect to said feeding means adapted to work up the material on said hearth, means for automatically stopping said carriage at the end of its feeding movement, and manually controlled means for starting said carriage.
45. 13. A smelting furnace, comprising, a Scotch hearth adapted to receive molten metal upon which floats the material to be smelted, a carriage mounted for movement along said hearth, a rabbling device mounted on said carriage, means for feeding said carriage along said hearth, means for operating said rabbling device in coöperative relation with respect to said feeding means adapted to work up the material on said hearth, means for automatically stopping said carriage at the end of the feeding movement for rendering said feeding and operating means inoperative, and manually controlled means for again rendering said feeding and operating means operative.
50. 14. A smelting furnace, comprising, a Scotch hearth adapted to receive molten metal upon which floats the material to be smelted, a carriage mounted for movement along said hearth, a rabbling device mounted on said carriage, means for feeding said carriage along said hearth, means for operating said rabbling device in coöperative relation with respect to said feeding means adapted to work up the material on said hearth, and means for varying the feed.
55. 15. A smelting furnace, comprising, a Scotch hearth adapted to receive molten metal upon which floats the material to be smelted, a carriage suspended in front of and for movement along said hearth, a

rabbling device mounted on said carriage, means for feeding said carriage along said hearth, and means for operating said rabbling device in coöperative relation with respect to said feeding means, adapted to work up the material on said hearth.

16. A smelting furnace, comprising, a Scotch hearth having an apron extending therealong adapted to receive the molten metal upon which floats the material to be smelted, a carriage suspended above said apron and for movement along said hearth, a rabbling device mounted on said carriage, means for feeding said carriage along said hearth, and means for operating said rabbling device in coöperative relation with respect to said feeding means, adapted to work up the material on said hearth.

17. A smelting furnace, comprising, a Scotch hearth adapted to receive molten metal upon which floats the material to be smelted, a carriage suspended above the hearth base in front of the hearth and for movement along the same, a rabbling device mounted on said carriage, means for feeding said carriage along said hearth, and means for operating said rabbling device in coöperative relation with respect to said feeding means, adapted to work up the material on said hearth.

18. A smelting furnace, comprising, a Scotch hearth, a carriage mounted for movement along said hearth, a rabbling device mounted on said carriage, means for feeding said carriage along said hearth, means for operating said rabbling device in coöperative relation with respect to said feeding means adapted to work up the material on said hearth, and a yielding connection between said rabbling device and said operating means.

19. A smelting furnace, comprising, a Scotch hearth adapted to receive molten metal upon which floats the material to be smelted, a carriage mounted for movement along said hearth, a rabbling device mounted on said carriage, means for feeding said carriage along said hearth, means for operating said rabbling device in coöperative relation with respect to said feeding means adapted to work up the material on said hearth, and a detachable connection between said rabbling device and said operating means.

20. In a smelting furnace, having an ore hearth adapted to receive molten metal upon which floats the material to be smelted, rabbling means comprising a carriage, means for feeding said carriage step by step, a rabbling device mounted on said carriage, and means for operating said rabbling device in coöperative relation with respect to said feeding means, adapted to work up the material on the hearth.

21. In a smelting furnace, having an ore hearth adapted to receive molten metal upon

which floats the material to be smelted, rabbling means comprising a carriage, means for feeding said carriage step by step, a rabbling device mounted on said carriage, means for operating said rabbling device in coöperative relation with respect to said feeding means adapted to work up the material on the hearth, and means for imparting a quick return movement to said carriage.

22. In a smelting furnace, having an ore hearth adapted to receive molten metal upon which floats the material to be smelted, rabbling means comprising a carriage, means for feeding said carriage step by step, a rabbling device mounted on said carriage, means for operating said rabbling device in coöperative relation with respect to said feeding means adapted to work up the material on the hearth, and means for imparting a quick return movement to said carriage with said rabbling device in withdrawn position.

23. In a smelting furnace, having an ore hearth adapted to receive molten metal upon which floats the material to be smelted, rabbling means comprising a carriage, a rabbling device mounted on said carriage, means for operating said device adapted to work up the material on the hearth, and a yielding connection between said operating means and said device.

24. In a smelting furnace, having an ore hearth adapted to receive molten metal upon which floats the material to be smelted, rabbling means comprising a carriage, a rabbling device mounted on said carriage, means for operating said device adapted to work up the material on the hearth, and a detachable connection between said operating means and said device.

25. A smelting furnace, comprising, a unitary ore hearth adapted to receive molten metal upon which floats the bed of ore and fuel, a rabbling device mounted for movement along and into said hearth, means for moving said rabbling device back and forth along said hearth, and means for operating said rabbling device, adapted to work up the bed in one direction along said hearth.

26. A smelting furnace, comprising, a unitary ore hearth adapted to receive molten metal upon which floats the bed of ore and fuel, a rabbling device mounted for movement along and into said hearth, means for moving said rabbling device back and forth along said hearth, and means for operating said rabbling device, adapted to work up the bed in one direction along said hearth, the length of said hearth being proportioned to correspond to the movement of said rabbling device therealong.

27. A smelting furnace, comprising, a unitary ore hearth adapted to receive molten metal upon which floats the bed of ore and fuel, a rabbling device mounted for move-

- ment along and into said hearth, means for moving said rabbling device back and forth along said hearth, and means for operating said rabbling device, adapted to work up the bed in one direction along said hearth, the length of said hearth and the movement of said rabbling device therealong being proportioned to correspond to the period of smelting of the ore added to the hearth.
- 10 28. A smelting furnace, comprising, a unitary ore hearth adapted to receive molten metal upon which floats the bed of ore and fuel, a rabbling device mounted for movement along and into said hearth, means for moving said rabbling device back and forth along said hearth, and means for operating said rabbling device, adapted to work up the bed in one direction along said hearth, with an intervening period of rest sufficient 20 to permit smelting of the ore added to the hearth.
- 25 29. A smelting furnace, comprising, a unitary ore hearth adapted to receive molten metal upon which floats the bed of ore and fuel, a rabbling device mounted for movement along and into said hearth, means for moving said rabbling device back and forth along said hearth, and means for operating said rabbling device, adapted to work up the bed progressively from one end of the 30 hearth to the other end thereof.
- 35 30. A smelting furnace, comprising, a unitary ore hearth adapted to receive molten metal upon which floats the bed of ore and fuel, a rabbling device mounted for movement along and into said hearth, means for moving said rabbling device back and forth along said hearth, and means for operating said rabbling device, adapted to work up the 40 bed progressively from one end of the hearth to the other end thereof, with an intervening period of rest for each portion of the bed sufficient to permit smelting of that portion.
- 45 31. A smelting furnace, comprising, a unitary ore hearth having a basin adapted to receive molten metal upon which floats the bed of ore and fuel, a rabbling device mounted for movement along and into said hearth, means for moving said rabbling device vice back and forth along said hearth, and means for operating said rabbling device,
- 50 adapted to work up the bed in one direction along said hearth.
32. A smelting furnace, comprising, a unitary ore hearth adapted to receive molten metal upon which floats the bed of ore and fuel, a rabbling device mounted for movement along and into said hearth, means for moving said rabbling device back and forth along said hearth, and means for operating said rabbling device while at rest in a direction along said hearth, adapted to work up the bed.
- 55 33. A smelting furnace, comprising, a unitary ore hearth adapted to receive molten metal upon which floats the bed of ore and fuel, a rabbling device mounted for movement along and into said hearth, means for moving said rabbling step by step along said hearth, and means for operating said rabbling device while at rest in a direction along said hearth, adapted to work up the bed.
- 60 34. A smelting furnace, comprising, a unitary ore hearth adapted to receive molten metal upon which floats the bed of ore and fuel, a rabbling device mounted for movement along and into said hearth, means for moving said rabbling device back and forth along said hearth, and means for operating said rabbling device, during its period of travel in one direction but while at rest in a direction along said hearth, adapted to work up the bed in one direction along said hearth.
- 65 35. A smelting hearth, comprising, an ore hearth adapted to receive molten metal upon which floats the bed of ore and fuel, a main hood over said hearth, a carriage mounted in front of said hood for movement along said hearth, a rabbling device mounted for movement on said carriage and into said hearth, mechanism for moving said carriage and said rabbling device thereon, and an auxiliary hood spaced from and between said main hood and said carriage, adapted to shield said carriage and facilitate the exhaust of the fumes from said hearth.
- 70 In testimony whereof I affix my signature this 18 day of March, 1916.
- 75 80 85 90 95 WILLIAM E. NEWNAM.
